UNITED STATES PATENT OFFICE.

JOSEPH J. RISCHARD, OF PASADENA, CALIFORNIA.

GREASE-GUN.

1,368,840.

Specification of Letters Patent. Patented Feb. 15, 1921.

Application filed August 4, 1919. Serial No. 315,281.

To all whom it may concern:

Be it known that I, JOSEPH J. RISCHARD, a citizen of the United States, residing at Pasadena, in the county of Los Angeles and State of California, have invented new and useful Improvements in Grease-Guns, of which the following is a specification.

My object is to make an improved grease gun, and my invention consists of the novel features herein shown, described and claimed.

Figure 1 is a sectional elevation of a grease gun embodying the principles of my invention.

Fig. 2 is an enlarged sectional detail on the line 2—2 of Figs. 1 and 3.

Fig. 3 is a cross sectional detail on the line 3—3 of Figs. 1 and 2.

The large pump cylinder 1 has a cap 2 fixed upon its lower end and a cap 3 removably mounted upon its upper end. A piston rod 4 is mounted through a stuffing box 5 in the cap 3. A piston 6 is fixed upon the lower end of the piston rod 4 and is operatively mounted in the cylinder 1.

The cap 3 has a bayonet slot 7 extending from its lower edge and a pin 8 is fixed in the cylinder 1 in position to enter the slot 7 and lock the cap 3 upon the cylinder 1. A handle 9 is fixed upon the upper end of the piston rod 4.

A small pump cylinder 10 is connected to the pump cylinder 1 near their upper ends by a pipe 11, and near their lower ends by a pipe 12. A valve seat 13 is fixed in the end of the pipe 12 near the small cylinder 10. Supports 14 and 14^a extend across the pipe 12. A valve 15 fits the valve seat 13 and a valve stem 16 is connected to the valve 15 and extends through bearings in the supports 14 and 14^a. A spring seat 17 is fixed upon the stem 16, and an extension coil spring 18 is mounted upon the stem 16 between the seat 17 and the support 14 so as to make a check valve which will open under pressure from the bottom of the large cylinder 1 and which will close under pressure from the bottom of the small cylinder 10.

A piston 19 is mounted in the small cylinder 10, a piston rod 20 being connected to the piston 19 and extending through the cap 21 screwed upon the upper end of the cylinder 10. A handle 22 is fixed upon the upper end of the piston rod 20, and a cap 23 is screwed upon the lower end of the cylinder 10. A spout 24 extends downwardly from the cap

23, and a plunger 25 extends downwardly from the piston 19 to enter the spout 24.

In the practical operation the cap 3 carrying the piston rod 4 and the piston 6 may be removed and the cylinder 1 filled with lubricant, the parts 3, 4 and 6 afterward replaced with the piston 6 on top of the lubricant. Then the handle 22 is operated to pull the piston 19 upwardly and the handle 9 operated to press the piston 6 downwardly to force the lubricant through the pipe 12 into the cylinder 10 below the piston 19. The end of the spout 24 may then be placed in the grease cup, the handle 22 being operated to move the piston 19 downwardly when the lubricant will be forced through the spout 24, and if it is desired to expel all of the lubricant the piston 19 may be forced downwardly until the plunger 25 fills the spout 24. If desired, the piston 19 may be raised to a point above the pipe 11 and the cylinders 1 and 10 may be filled at the same time. The check valve in the pipe 12 holds the lubricant from running back into the cylinder 1. The handle 9 may be depressed to force the lubricant through the pipe 12 and then the handle 22 operated to expel the lubricant from the spout 24. The quantity may be regulated by accurately manipulating the handles 9 and 22.

Various changes may be made without departing from the spirit of my invention as claimed.

I claim:

1. A grease gun comprising a large cylinder; a piston in the large cylinder; a small cylinder; a piston in the small cylinder; pipes connecting the ends of the cylinders together; a check valve in the lower connecting pipe; and a spout extending from the small cylinder.

2. A grease gun comprising a large cylinder, a piston in said large cylinder, a small cylinder, a piston in said small cylinder, a pipe connecting the lower end of said cylinders, and a spout projecting from the lower end of said small cylinder.

3. A grease gun including a large cylinder, a piston in said large cylinder, a small cylinder, a piston in said small cylinder, a pipe connecting the lower end of said cylinders, a check valve in said pipe to prevent the grease from passing from said small cylinder into said large cylinder, and a spout projecting from the lower end of said small cylinder.

4. A grease gun including a large cylinder, a small cylinder, a piston in said large cylinder, a piston in said small cylinder, a pipe connecting the lower end of said cylinders, a spout leading from the lower end of said small cylinder, and a plunger on the piston in said small cylinder for projecting into said spout.

5. A grease gun including a large cylinder, a piston in said large cylinder, a small cylinder, a piston in said small cylinder, a

pipe connecting the lower end of said cylinders, a check valve in said pipe to prevent the grease from passing from said small cylinder into said large cylinder, a spout projecting from the lower end of said small cylinder, and a plunger on the piston in said small cylinder for projecting into said spout. 15

In testimony whereof I have signed my name to this specification.

JOS. J. RISCHARD.
